CLAIM

The ornamental design for a windshield cover, as shown and described.

DESCRIPTION

FIG. 1 is a front elevational view of a windshield cover showing my new design;

FIG. 2 is a top plan view thereof;

FIG. 3 is a rear elevational view thereof;

FIG. 4 is a bottom plan view thereof;

FIG. 5 is a right side elevational view thereof, the left side being a mirror image of that shown; and

FIG. 6 is a right, front perspective view of a windshield cover showing a second embodiment of my new design wherein the sole difference resides in the simulation of sunglasses on the front surface thereof.
